* cited by examiner

Primary Examiner — Ian Simmons*Assistant Examiner* — Shannon Morgan(74) *Attorney, Agent, or Firm* — Jon Gibbons; Fleit Gibbons Gutman Bongini & Bianco P.L.(57) **CLAIM**

The ornamental design for a display screen or portion thereof with graphical user interface, as shown and described.

DESCRIPTION

The sole FIGURE is a view of a display screen or portion thereof with graphical user interface showing the new design. The broken lines shown in the sole FIGURE represent a display screen or portion thereof; the broken lines form no part of the claimed design.

1 Claim, 1 Drawing Sheet
